CLAIM

The ornamental design for a motorcycle wheel, as shown and described.

DESCRIPTION

FIG. 1 is a side elevation view of a motorcycle wheel showing my new design, the opposite side being a mirror image of the side shown herein;

FIG. 2 is a cross-section view taken along line 2—2, in FIG. 1; and

FIG. 3 is a cross-section view on an enlarged scale taken along line 3—3, in FIG. 1.

FIG. 2

FIG. 3
